UNITED STATES PATENT OFFICE.

LOUIS E. PARENT, OF CLAREMONT, NEW HAMPSHIRE, ASSIGNEE TO CLAREMONT WASTE MANUFACTURING COMPANY, A CORPORATION OF NEW HAMPSHIRE.

ROTARY CUTTER.

Application filed May 3, 1927. Serial No. 188,459.

My invention relates to rotary cutters. It has for its object to provide an improved rotary cutter, and more particularly an improved flock cutter. A further object of my invention is to provide improved cooling means for such a cutter whereby the temperature of the working parts, and consequently of the flock, is substantially reduced in such manner as to reduce the danger from fire and thereby to increase the productive capacity of the cutter.

In the accompanying drawings, I have shown, for purposes of illustration, one embodiment which my invention may assume in practice.

In these drawings,—

Figure 1 is a transverse sectional view of a cutter equipped with my improvement;

Fig. 2 is a side elevation, partially in section, of my improved bed.

Fig. 3 is a longitudinal section on line 3—3 of Fig. 2;

Fig. 4 is a transverse sectional view on line 4—4 of Fig. 2;

Fig. 5 is a transverse sectional view on line 5—5 of Fig. 2, and

Fig. 6 is a reduced longitudinal sectional view of the cylinder.

In this illustrative construction I have shown my invention embodied in a flock cutter of the construction described and claimed in my co-pending application, Serial No. 188,458 filed May 3, 1927, the same, however, being provided with improved bed cooling means cooperating in an improved manner with my improved water cooled tool carrying cylinder described in that application.

As to the cooling means of the cylinder, it is believed sufficient to say that the cylinder 1 is preferably provided with a suitable water inlet 2 at one end thereof so that water is continuously supplied through a port 3 into a cylindrical chamber 4 within the cylinder and out of that chamber through a port

5 to a discharge 6 at the opposite end of the cylinder, the inlet 2 and discharge 6 being on opposite sides of an abutment or plug 7 carried in a pipe 8 which in this construction extends continuously through the cylinder 50 and the arrangement being such that water is caused to flow into one end of the cylinder and through the latter in such manner as effectually to cool the cylinder, and then out at the opposite end of the cylinder.

55 My improved bed cooling means form-

ing the subject matter of this application is adapted to cooperate with the water cooling means of the cylinder just described, in an improved manner, the same being so constructed and arranged that the cooling water supplied to the bed is adapted to be delivered to the latter at a point midway between the ends of the cylinder and to be discharged from the bed at the opposite ends of the cylinder in such manner as to cooperate with the flow of cooling water in the cylinder in keeping down the temperature. Considering the bed more in detail, it will be noted that, while of the construction described and claimed in my co-pending application Serial No. 187,570 filed Apr. 29, 1927, the bed is provided with a cooling water inlet 9 at the bottom of the middle transverse passage 10 therein. Moreover, this passage 10 communicates at its upper ends with longitudinal passages 11, 12 which in turn communicate with other transverse passages 10 on opposite sides of the inlet 9, the passages 10, 11 and 12 extending underneath and on opposite sides of the knife socket 13 of the bed. Thus, water entering through the inlet 9 may flow longitudinally of the bed in opposite directions from the inlet to opposite ends of the bed with transverse passages 10 connecting the longitudinal passages 11 and 12 in each half. Moreover, it will be noted that at each of the opposite ends of the bed suitable outlet pipes 14 and 15 are provided in the tops of the longitudinal passages 11 and 12. Thus it will be observed that the water entering at the inlet 9 is caused to pass transversely and longitudinally in opposite directions from an inlet at the bottom of the bed and midway between the ends thereof, to the opposite ends of the bed, and there to be discharged from the top of the bed, the advantages of the bottom inlet and top discharge of my previous application being thus obtained, but in each half of the bed.

In the operation of my improved construction, the cooling water flowing through the bed cooperates with the water flowing through the cylinder, in such manner as to reduce the temperature not only of the bed but of the cylinder as well as of the flock and the casings of the mechanism. More particularly, the water entering the bed at its minimum temperature serves to reduce the temperature of the bed at its middle, i. e. at a

point between the ends of the cylinder and where the water in the cylinder, then having passed approximately halfway through the latter, is somewhat heated. Further, the 5 cooling water entering the bed at the middle of the latter and then dividing and passing in opposite directions longitudinally of the bed, is cooler for the greater part of its travel than the water in the corresponding part of the cylinder, so that it further tends to keep 10 down the temperature as it moves toward its outlets at the opposite ends of the bed. More particularly, the water in the half of the bed adjacent the cylinder outlet is cooler than 15 the water in that portion of the cylinder, so that as a result the temperature at the end of the cutter at which the cylinder discharges is considerably reduced. Considering the other half of the bed, the temperature at the end 20 of the bed at which the water enters the cylinder is similarly lowered, this also effecting some reduction in the temperature of the water in the cylinder flowing to the outlet half of the device, and thus helping in lowering 25 the terminal temperature. From the angle of the bed alone, it will also be clear that the middle of the bed being cool and the length of travel of the cooling water from the center to the opposite bed ends being 30 short, the temperature of the bed as a whole is reduced, with a consequent reduction in the temperature of the knives, casing, cylinder and other associated parts as well as of the flock. These and other advantages of my 35 improved construction will, however, be clearly apparent to those skilled in the art.

While I have in this application specifically described one embodiment which my invention may assume in practice, it will be 40 understood that this form of the same is used for purposes of illustration only, and that the invention may be modified and embodied in various other forms without departing from its spirit or the scope of the 45 appended claims.

What I claim as new and desire to secure by Letters Patent is:

1. In a rotary cutter comprising a cylinder and bed, means for maintaining a flow of 50 cooling fluid longitudinally of the cylinder, and means for circulating cooling fluid through the bed having the point of maximum cooling of the bed between the ends of the cylinder and cooling streams flowing from said point to opposite ends of the bed.

2. In a rotary cutter comprising a cylinder and bed, means for maintaining a flow of 55 cooling fluid longitudinally of the cylinder, and cooling means for the bed having the cooling fluid entering the latter midway between the ends of the cylinder and discharging at the opposite ends thereof.

3. In a rotary cutter comprising a cylinder and bed, means for maintaining a flow of 60 cooling fluid longitudinally of the cylinder,

and cooling means for the bed entering the bed between the ends of the cylinder and at the bottom of the bed and discharging at the opposite ends of the cylinder at the top of the bed.

4. In a rotary cutter comprising a cylinder and bed, cooling means delivering cooling water from end to end of the cylinder, and cooling means for the bed having an outlet 70 at the outlet end of the cylinder and an inlet nearer the inlet end of the cylinder.

5. In a rotary cutter comprising a cylinder and bed, cooling means delivering cooling water from end to end of the cylinder, and cooling means for the bed having an outlet 80 at the outlet end of the cylinder and an inlet nearer the inlet end of the cylinder, said bed inlet being at the bottom of the bed and said bed outlet being at the top of the bed.

6. In a rotary cutter comprising a cylinder and bed, cooling means delivering water from end to end of the cylinder, and cooling means for the bed having an inlet, outlets at the outlet end of the cylinder, and a second set of outlets at the inlet end of the cylinder.

7. In a rotary cutter comprising a cylinder and bed, cooling means delivering water from end to end of the cylinder, and cooling means for the bed having an inlet and having outlets at the opposite ends of the cylinder and 95 equally spaced from the bed inlet.

8. In a rotary cutter comprising a cylinder and bed, cooling means for the cylinder delivering cooling water from end to end of the cylinder, and cooling means delivering cooling water transversely and longitudinally of the bed in opposite directions from a point between the ends of the bed.

9. A water cooled bed for rotary cutters having inlet means between its ends and outlets at its opposite ends communicating with 105 said inlet means.

10. A water cooled bed for rotary cutters having an inlet between its ends and outlets at its opposite ends each communicating with 110 the same inlet.

11. A water cooled bed for rotary cutters having inlet means between its ends and outlets at its opposite ends each communicating with said inlet means and equally spaced from 115 said inlet means.

12. A water cooled bed for rotary cutters having inlet means between its ends and outlets at its opposite ends, said outlets being disposed at levels substantially above said inlet 120 means.

13. A water cooled bed for rotary cutters having cooperating longitudinal and transverse passages, inlet means connected to one of the transverse passages between the ends 125 of said bed, and outlet means connected to said longitudinal passages at opposite ends of said bed.

14. A water cooled bed for rotary cutters having cooperating longitudinal and trans-

verse passages, inlet means connected to one of the transverse passages between the ends of said bed, and outlet means connected to said longitudinal passages at opposite ends of said bed, said outlets being disposed substantially above said inlet means.

15. A water cooled bed for rotary cutters having a bed socket therein, cooling water

passage means for cooling the sides and bottom of said socket, inlet means connected to said cooling means substantially midway between the ends of the socket, and outlets communicating with said cooling means at the opposite ends of the socket.

In testimony whereof I affix my signature.

LOUIS E. PARENT.
